UNITED STATES PATENT OFFICE

WALTER ERNST, OF MOUNT GILEAD, OHIO, ASSIGNOR TO HYDRAULIC PRESS
MANUFACTURING COMPANY, OF MOUNT GILEAD, OHIO

HYDRAULIC PRESS

Application filed June 27, 1929. Serial No. 373,985.

This invention relates to hydraulic presses which are intended to be operated by fluid supplied under pressure from a constant discharge pump, and more particularly to that 5 type of press which may be set either to automatically perform an indeterminate number of successive pressing operations, or to perform one complete pressing operation, at the end of which the press platen is automatically brought to rest. The present invention also embodies certain changes in and additions to the valves and valve operating mechanism shown and described in my application for Letters Patent Serial No. 334, 10 746, filed January 24, 1929.

In the above named application I have described a hydraulic press connected in a hydraulic circuit and arranged to be operated by fluid under pressure delivered by a 20 variable discharge rotary pump also connected in the circuit, the valves and valve operating mechanism controlling the flow of fluid in the circuit being so arranged that the pump is dischargeable in one direction 25 only. By this arrangement, whereby the pump is dischargeable in one direction only, so that it is unnecessary to shift the heavy pump cross head in order to effect a reversal of the direction of fluid travel in the circuit, 30 a high press operating speed is attainable.

The valves and valve operating mechanism embodying the invention described in said application include a reversing valve located in the surge tank and serving to control 35 the direction of travel of high pressure fluid, and a pilot valve connected in a separate low pressure hydraulic circuit and having connection to the reversing valve independently of the high pressure circuit for effecting movements of the reversing valve to reverse the 40 direction of travel of high pressure fluid. Platen-actuated mechanical means are provided for moving the cross head of the variable discharge pump to a neutral position when the 45 platen reaches the top of its upward or return stroke, thereby causing the platen to dwell in its uppermost position until the high pressure reversing valve is shifted to produce a pressing stroke of the platen. It is 50 to be noted that the ability of the platen to

dwell in its uppermost position is dependent upon the placing of the pump cross head in a neutral position. Obviously, this arrangement of valves, if used in connection with a constant delivery pump, could not be 55 adapted to bring the platen to a dwell when desired, because the construction of such a pump would not permit its discharge being reduced to zero without completely stopping the pump. Therefore, when using a constant delivery pump in connection with a high pressure hydraulic circuit similar to that outlined above, it is necessary that means be provided for diverting the high pressure pump discharge away from the 60 platen returning cylinders, and for by-passing the discharge directly into the surge tank in order that the platen will be brought to a dwell in its uppermost position.

Accordingly, the main object of my invention 70 is to provide means for operating a hydraulic press including a high pressure circuit for producing reciprocatory movements of the press platen, which circuit is supplied with fluid under pressure by a constant discharge pump, and means automatically operative when the platen reaches its 75 uppermost position for diverting the high pressure fluid from the platen returning cylinders and for returning the fluid directly 80 to the surge tank.

Another object of the invention is to provide pressure responsive means for reversing the direction of movement of the press platen when the latter encounters resistance to 85 its downward travel irrespective of the position of the platen, and separate means actuated by the platen and adjustable independently for causing the platen to automatically 90 perform an indeterminate number of pressing and return strokes or to cause the platen to perform a single pressing stroke and a return stroke and to then be brought to rest in its uppermost position. Other objects will 95 become apparent from a reading of the following description, the appended claims and the several views illustrated in the drawings in which:

Fig. 1 is a front elevation of a hydraulic 100

press showing some of the operating parts embodying my invention,

Fig. 2 is a central vertical sectional view of the upper end of a main pressing cylinder 5 and a surge shifting valve mounted thereon,

Fig. 3 is a view showing the general piping arrangement in diagrammatic form and showing in section a by-pass valve and a platen-operated valve for controlling the 10 movements of the by-pass valve,

Fig. 4 is a longitudinal sectional view of a pilot valve,

Fig. 5 is a longitudinal sectional view of a reversing valve, and

15 Fig. 6 is a detail sectional view of one end of a piston valve.

Fig. 7 is a fragmentary sectional view taken on the line 7—7 of Fig. 4.

20 Fig. 8 is a detail view of a pilot valve actuating rod and associated parts.

The invention may be embodied in various types of hydraulic motors, but in the accompanying drawings it is illustrated in connection with a press of the four column downward pressure type. Referring to the drawings, there is shown a hydraulic press A, having a base B, a stationary table C, a press head D connected to said table by four strain rods E, and a reciprocating platen F guided 25 on the strain rods E in the usual manner.

It is to be understood that the present invention includes two entirely separate hydraulic circuits, one being a high pressure press operating circuit and the other being 30 a low pressure pilot circuit. The low pressure circuit is used to effect the shifting of a reversing valve in the high pressure circuit for producing resultant reciprocating movements of the press platen. These two circuits will be first outlined and the various 35 valves and valve operating mechanisms included in each of the circuits will be subsequently described in detail.

With reference to the high pressure circuit, a constant discharge pump 1 is connected to a surge tank 2 by means of the suction pipe 3, as shown in Figure 3, and supplies fluid under high pressure to said circuit. The discharge of the pump is directed 40 through a pipe line 4 which is connected to the reversing valve 5. The valve 5 also has connected to it the pipe line 6, which leads to booster cylinders 7 and to one side of a surge shifting valve 8 located in the surge 45 tank 2, and a pipe line 9 which leads to push back or platen returning cylinders 10 and to the other side of the surge shifting valve 8. The reversing valve is located within the 50 surge tank 2 and is provided with exhaust openings communicating with the surge tank.

The construction and the operation of the reversing valve 5 will be hereinafter described in detail, but for the sake of clearness it will, for the present, be sufficient to

say that the valve is adapted to be set in either of two positions, in the first of which positions the pipe line 4 is placed in communication with the pipe line 6, and the pipe line 9 with the surge tank by means of one 70 of the aforementioned exhaust openings, and in the second of which positions the pipe line 4 is placed in communication with the pipe line 9, and the pipe line 6 with the surge tank by the other of the aforementioned exhaust openings.

The low pressure pilot circuit includes a pipe line 11 which communicates with the surge tank, a low pressure pump 12 arranged to receive its intake from the pipe line 11, and a low pressure discharge pipe line 13 connected to the pump and to a pilot valve 14. A pipe line 15 connected to the pilot valve and to the surge tank 2 affords communication therebetween, and it will 80 thus be seen that the pipe line 11, the pump 12, the pipe line 13, the pilot valve 14, the pipe line 15, and the surge tank 2 comprise the entire low pressure hydraulic pilot circuit. Separate pipe lines 16 and 17 connect the pilot valve to a pressure responsive valve actuating device G associated with the reversing valve, but it is to be noted that the pipe lines 16 and 17 form no part of the low pressure circuit. The pilot valve is so arranged that, upon being shifted in one direction, fluid under pressure from the low pressure pilot circuit will be introduced through the pipe line 16 into one side of the pressure responsive valve actuating means G to 90 shift the reversing valve in one direction, and when the pilot valve is shifted in the opposite direction fluid under pressure from the low pressure pilot circuit will be introduced through the pipe line 17 into the opposite side of the pressure responsive valve actuating means G and will move the reversing valve in the opposite direction.

The surge shifting valve 8 is provided with a valve casing 18 having a valve chamber 19 which communicates with the surge tank 2 by means of a port 20, and with the main cylinder 21 of the press by means of a port 22. Slidably mounted in the chamber 19 is a balanced piston valve 23, said valve being provided at one of its ends with a tail rod 24, the tail rod being slidable in a bore 25. The bore 25 communicates with the chamber 19 by means of a passage 26, and also with the pipe line 6. The valve 23 is also provided with a second tail rod 27 which extends through a chamber 28 into a bore 29 in a casing 30 attached to the casing 18 and into a chamber 31 in said casing 30, the chamber 31 communicating at its outer end with the pipe line 9. It may be noted that, when the piston valve 23 is in the position shown in the drawings, the main cylinder 21 communicates with the surge tank 2 by means of the port 22, the chamber 105

19, and the port 20, but, when the piston valve is caused to be shifted to the left in a manner to be hereinafter described, the cylinder 21 will communicate with the pipe line 6 by means of the port 22, the chamber 19, the passage 26, and the bore 25.

Mounted on the top of the valve casing 18 and adapted to communicate with the chamber 28 is a check valve 32, which comprises a casing 33 having ports 34, 34, and 35 and a valve ball 36 which is urged to closed position by a spring 37, the tension of which spring may be adjusted by means of a threaded plug 38 for a purpose hereinafter specified. It is to be noted that, when the piston valve 23 is moved to the left in the plane of the drawings, fluid contained in the chamber 28 will be expelled through the check valve 32 into the surge tank 2, but that no fluid will enter the chamber 28 through said check valve at any time.

Mounted on the bottom of the casing is a second check valve 39 adapted to communicate with the chamber 28 by means of a port 40 and with the surge tank 2 by means of a port 41. A valve ball 42 in the check valve 39 is kept seated by gravity, and by the pressure in the chamber 28, so that when the piston valve 23 moves to the right in the plane of the drawings the ball will be lifted from its seat by the suction created in the chamber 28, thus allowing fluid to flow from the surge tank 2 through the ports 41 and 40 into the chamber 28.

With more particular reference to the reversing valve 5, there is shown in Figure 5 a valve casing 42^a having a central chamber 43 and a piston valve 44 slidable longitudinally in the chamber and provided at its opposite ends with valve heads 44^a and 44^b. In order to facilitate the connecting of the reversing valve to the pipe lines 6 and 9, there are provided detachable plates 45 and 46 bolted to the valve casing 42^a, shoulders 47 on said plates fitting within counter bores 48 in the valve casing, and clamping packing 49 in said bores, thus forming a pressure tight joint between the casing and the plates. The plates are provided with threaded bores which receive the ends of the pipes 6 and 9, and these bores register respectively with ports 50 and 51 formed in the valve casing 42^a. A similar plate 52 is bolted to the valve casing midway between the ports 50 and 51 and is provided with an opening 53 which communicates with the chamber 43, and in which opening the pipe line 4 is connected. It will be apparent that, when the piston valve 44 is in the position shown in Figure 5, the pipe line 4 will communicate with the pipe line 6 by means of the opening or port 53, the valve chamber 43, and the port 50. When the piston valve is moved to the left the pipe line 4 will be placed in communication with the

pipe line 9 by means of the opening 53, the valve chamber 43, and the port 51.

When the valve is in the position shown in Figure 5, and the pipe line 4 is in communication with the pipe line 6, it is necessary that the pipe line 9 be placed in communication with the surge tank. To this end, the valve head 44^a is provided with an annular recess 54 arranged to communicate with a transversely disposed opening 55 extending inwardly from said annular recess towards the center of the valve head 44^a and communicating with a port 56 formed in the valve and extending from the transverse opening 55 to the adjacent outer end of the piston valve. The outer end of the port 56 is enlarged and threaded to receive a removable plug 56^a having a central opening 56^b extending longitudinally therethrough to register with the opening 56. It will be seen that fluid in the pipe line 9 will enter the annular recess 54, then pass into the transverse opening 55, and then out through the port 56 and the opening in the plug and into the surge tank, the end of the piston valve 44 being constantly exposed to the fluid in the surge tank. When the piston valve is moved to the left in the plane of the drawings, the annular recess 54 will be moved to the left of the port 51 as viewed in Figure 5 and communication between the pipe line 9 and the surge tank will be thereby cut off. It is now necessary that, with the valve in this new position, the pipe line 6 be placed in communication with the surge tank. For accomplishing this purpose I provide the valve casing with a chamber 57 located to the right of the piston valve and also provide said chamber with a plurality of relief openings 58 extending through the valve casing and communicating with the surge tank. When the piston valve has moved to the left, the valve head 44^b will move to the left of the port 50, and the pipe line 6 will be placed in communication with the port 51, the valve chamber 43, the chamber 57, and the openings 58.

Inasmuch as the pump 1 is arranged to deliver a continuous discharge it is desirable that the reversing valve be so constructed that the ports 50 and 51 will not be completely covered simultaneously by the valve heads 44^b and 44^a respectively when the piston valve 44 is in an intermediate position while being shifted from one extreme position to the other, because if these ports were so simultaneously covered, the discharge of the pump would be entrapped between the valve heads and the pump, and associated piping would be subjected to a severe momentary shock. In order to avoid the entrapping of the pump discharge when the valve is being shifted, the port 50 is made wider than the valve head 44^b and the port 51 is made wider than either of the portions

of the valve head 44^a which lie on opposite sides of the annular recess 54. Because of this construction, when being shifted from one extreme position to the other, the valve 5 heads will at no time completely cover the ports 50 and 51 so that it is impossible to entrap the pump discharge between said heads. Thus, when the piston valve is moved to the left from its Figure 5 position 10 to an extent just slightly greater than the width of the head 44^b, the pump discharge will communicate with the pipe line 6, the pipe line 9 and with the surge tank by means of the chamber 57 and the ports 58, and also 15 by means of the opening 55, the port 56, and the opening 56^b. When the piston valve has moved farther to the left so as to cut off communication of the pump with the opening 55, and with the chamber 57, fluid under 20 pressure will be delivered to the push back cylinders through the pipe line 9.

For guiding the right hand end of the piston valve when the head 44^b is positioned between the walls of the port 50, the valve 25 is provided with a plurality of radially disposed longitudinally extending ribs 59 adapted to slide in the valve casing and to thereby maintain the piston valve centrally 30 in the valve chamber.

For shifting the valve 44 in either direction, I provide the pressure responsive valve actuating means G located at the outer end 35 of the reversing valve. This valve actuating means includes a pressure chamber 60 formed in the outer end of the valve casing 42^a, a port 61 communicating with the inner end of the chamber 60 and with the pipe line 16, a port 62 communicating with the outer end of the chamber 60 and with the pipe line 40 17, a piston rod or stem 63 extending from the valve 44 and into the chamber 60, and a piston 64 fixed to the outer end of the rod 63 and mounted for reciprocatory movements 45 in the chamber 60. It is apparent that, when fluid under pressure is admitted from the low pressure pilot circuit through the pipe line 17 and into the outer end of the chamber 60, the piston 64 will be moved to the left as viewed in Fig. 5, and the valve 44 50 will be shifted to place the pipe line 4 in communication with the pipe line 9, and the pipe line 6 in communication with the surge tank. In a similar manner, when fluid under pressure is admitted from the low pressure 55 pilot circuit through the pipe line 16 and into the inner end of the chamber 60, the piston 64 and the valve 44 will be returned to the position shown in Figure 5, thereby placing the pipe line 4 in communication with the pipe line 6, and the pipe line 9 in communication with the surge tank.

The pilot valve 14 is used to direct fluid from the low pressure pilot circuit first into the pipe line 16 to shift the piston valve 44 60 to the right as viewed in Figure 5, and then

to introduce fluid under pressure from the low pressure pilot circuit into the pipe line 17 to shift the piston valve 44 to the left. The pilot valve shown in detail in Fig. 4, includes a valve casing 65 formed with a 70 valve chamber 66, which chamber communicates with the pipe line 13 by means of a port 67 formed in the casing. The chamber 66 is also arranged to communicate with the pipe line 16 by means of an outlet port 68 75 and to communicate with the pipe line 17 by means of an outlet port 69. Slidably mounted in the bore forming the chamber 66 is a piston valve 70 having a stem 71 extending from one end of the valve through 80 packing 72 held in place by a gland nut 73 threadably mounted in an end cap 74 secured to the outer end of the valve casing. The stem 71 extends through and somewhat beyond the gland nut 73 and is provided 85 with a flange 75 located within the valve chamber and adapted to abut an inwardly extending flange 76 on the end cap 74, thus limiting the travel of the valve 70 to the right. When the valve 70 is in the position 90 shown in the drawings, that is, in its extreme right hand position, the pipe line 13, receiving fluid from the low pressure pump 12, will communicate with the pipe line 17 by means of the port 67, the valve chamber 95 66, and the port 69, whereas, when the valve 70 is moved to the left, the pipe line 13 will communicate with the pipe line 16 by means of the port 67, the valve chamber 66, and the port 68. 100

When the valve 70 is in the position shown in Figure 4, in which position of the valve the pipe line 13 communicates with the pipe line 17, it is necessary that the pipe line 16 communicate with the surge tank in order 105 that the pressure acting through the pipe line 17 may be able to move the piston 64 of the reversing valve. To this end I provide the pilot valve with a port 77 which communicates with the valve chamber 66 110 and with the pipe line 15, which pipe line is in constant communication with the surge tank, and a cored passage 78 formed in the valve casing to connect the end portions of the chamber 66 located on opposite sides of 115 the piston valve 70. When the valve 70 is in the position shown in Figure 4, the pipe line 16 will communicate with the pipe line 15 by means of the port 68, the valve chamber 66, the cored passage 78, and the port 120 77. When the piston valve 70 is moved to the left in the plane of the drawings, the pipe line 17 will communicate with the pipe line 15 by means of the port 69, the valve chamber 66, and the port 77. 125

As stated above, the pipe lines 16 and 17 leading from the pilot valve to the chamber 60 in the reversing valve do not form a part of the low pressure circuit, and, after fluid under pressure acting through either of these 130

pipe lines has acted to shift the piston 64, there will be no further flow of fluid through either of said pipe lines. Since the low pressure pump delivers a continuous discharge, it is necessary that means be provided for directing the discharge of the pump into the surge tank during intervals between movements of the piston 64. For accomplishing this purpose the 10 pilot valve 14 is provided with a relief valve H. This relief valve includes a plunger 79 slidably mounted in a sleeve 80 rigidly mounted in a bore 81 formed in the valve casing 65 and adapted to communicate with the port 67 and the pipe line 13 by means of a port 82. The sleeve 81 is provided with an opening 83 extending through the wall of the sleeve and communicating with a port 84 formed in the 15 valve casing to communicate with the valve chamber 66 at the inner end thereof. The plunger 79 is provided at one of its ends with a flare 85 adapted to abut an inwardly extending flange 86 formed in the valve 20 casing and to thus limit the movement of the plunger in one direction. The valve casing 65 is further provided with a spring chamber 87 concentrically arranged with the plunger 79, and positioned within this 25 spring chamber is a coiled spring 88 interposed between the end of the plunger 79 and a threaded plug 89 screw threaded into the spring chamber, the spring serving to urge the plunger 79 to a closed position, in which 30 position the inner end portion of the plunger extends past the slot 83. A hollow nut 90 is screw threaded on the plug 89 for covering the latter, and also serves as a lock nut to retain the plug 89 in adjusted position. The port 84 communicates with the 35 spring chamber 87 by means of a cored passage 91. When the piston valve 70 is moved to the left, fluid will be admitted from the low pressure pilot circuit through the pipe line 13, the port 67, the valve chamber 66, the port 68, and the pipe line 16 into the inner end of the chamber 60 in the reversing valve, thereby moving the piston 64 to the right, as viewed in Figure 5. When the 40 piston 64 has been moved to its extreme right hand position so that there can be no further flow of fluid through the pipe line 16, the pressure in the low pressure pilot circuit will build up and will move the relief valve 45 plunger 79 against the pressure exerted by the spring 88 until the inner end of the plunger has moved to place the port 82 in communication with the port 84 by means of the opening 83, at which time the low pressure fluid will be discharged from the pipe line 13 through the ports 67 and 82, the opening 83, the port 84, the cored passage 78, the port 77, and the pipe line 15 into the surge tank. It is to be noted that the 50 spring chamber 87 is in constant communication with the surge tank by means of the cored passage 91, the port 84, the cored passage 78, the port 77, and the pipe line 15, so that the static pressure of the fluid in the surge tank acts upon the outer end of the plunger 79 and thus aids the spring 88 to urge the plunger to its closed position.

Rigidly fixed to the valve casing 65 is a separate casing 92, which casing is provided with a chamber 93 and with inwardly extending flanges 94 and 95 concentrically aligned with the valve chamber 66 of the pilot valve. Slidably mounted in the casing 92 is a valve actuating plunger 96. The plunger 96 is provided with a stem 97, which projects into the valve chamber 66 of the pilot valve, and a flange 98 on the plunger is adapted to seat in a recess 99 formed in a bushing 100 mounted in adjacent and concentric counter bores 101 and 102 in the casings 92 and 65, thus limiting the movement of the plunger 96 in one direction. The plunger 96 is also provided with another stem 103 extending through packing 104 and a gland nut 105 screw threaded into an opening 106 in the end of the casing 92. The outer end portion of the stem 103 is threaded to receive a hand wheel 107, and interposed between the hand wheel and the gland nut 105 is a coil spring 108 and a spring seat 109. The hand wheel 107 is screwed on the stem 103 to place the spring under compression so that the hand wheel, the stem 103, and the plunger 96 will be constantly urged outwardly. A second and smaller hand wheel 110 is screw threaded on the end of the stem and drawn up tight against the hand wheel 107 for locking the latter and retaining it against accidental displacement from its adjusted position.

The plunger 96 is of slightly greater diameter than the stem 103 and forms therewith a resultant shoulder 111, which shoulder is at all times disposed within the chamber 93. Connected to the casing 92 and arranged to communicate with the chamber 93 therein is a pipe 112 which is also connected to the pipe line 6, so that the chamber 93 is in constant communication with the pipe line 6. It will be apparent that, when the piston valve 70 of the pilot valve is in its left hand position, a building up of pressure in the pipe line 6 will result in a corresponding building up of pressure in the chamber 93, and when a predetermined pressure has been reached, which pressure is determined by the amount of pressure exerted by the spring 108, the plunger 96 will be moved to the right in the plane of the drawings until the stem 97 carried by the plunger engages the piston valve 70 and moves it to the right, that is, moves it into the position shown in Figure 4.

For moving the piston valve 70 to the left as viewed in Figure 4, I provide mechanical

platen actuated means adapted to engage the end of the stem 71.

Referring to Figure 1, there is shown a vertically disposed operating rod 113 slidably mounted in lugs 114 and 115 on the stationary table C and the press head D respectively, the downward movement of said rod being limited by a collar 115^a adjustably fixed to the rod. The rod 113 is constantly urged to its lowermost position by gravity, and also by means of a coiled spring 116 mounted on the rod between the lug 115 and a collar 117 also on said rod. A boss 118 fixed to the platen F is arranged to slide freely on the rod 113. Adjustably mounted on the rod 113 is a collar 119 which is adapted to be engaged by the boss 118 when the platen has reached a predetermined point in its upward travel, the rod 113 being thereby lifted. As shown in Fig. 8, the upper end of the rod 113 is provided with an inwardly extending recess 120, and, adjacent the extreme upper end portion of the rod, with a pair of oppositely disposed slots 121. Slidably mounted in the recess 120 is a rod 122 provided with a pin 123 which extends through and is rigidly attached to the rod, and has its opposite end portions projecting through the slots 121. A coil spring 124 is located in the recess 120 and is disposed between the bottom of the recess and the inner end of the rod 122, the spring constantly urging the rod to its uppermost position, in which position the pin 123 contacts with the upper end walls of the slots 121. A bell crank lever 125 is pivotally connected to the press head D as at 126. One arm 127 of the bell crank lever is pivotally connected to a head 128 on the rod 122 as at 129. The other arm 130 of said lever is provided with a rounded head 131 adapted to engage the stem 71 of the pilot valve and to move it inwardly when the rod 113 is lifted. The spring 124 urges the rod 122 to its uppermost position at all times, and serves as a cushion for relieving the pilot valve of any undue shock which might otherwise occur if the connections between the operating rod and the valve stem were rigid.

Attention is called to the fact that, although the piston valve 70 of the pilot valve has no permanent connection either to the stem 97 or to the bell crank lever 125, the piston valve is disposed in a horizontal plane and will be retained in either of its positions by the frictional contact of the packing 72 with the stem 71, until said piston valve is positively shifted in the manner described above.

A manually operable lever 132 is pivotally mounted on the base B as at 133, and one arm 134 of said lever is provided with a rounded head 135 adapted to engage the lower face of a collar 136 fixedly mounted on the operating rod 113 and to lift said

rod when the lever is swung in a clockwise direction as viewed in Figure 1. A coil spring 137 interposed between the base B and the arm 134 of the lever tends to cause a lug 138 on said lever to abut a lug 139 on the base, thereby normally maintaining the lever in the position shown in Figure 1. It is to be noted that, when the rod 113 is caused to perform a reciprocatory motion during automatic operation of the press, the collar 136 will move towards and away from the head 135 and there will be no danger of the lever 132 swinging outwardly and striking the operator.

It is to be noted that the piston valve 44 of the reversing valve 5 is adapted to be moved into two extreme positions for producing reciprocatory movements of the platen, and that the means provided for moving the piston valve is adapted to move it from one extreme position to the other, but is not adapted to maintain the valve in a neutral position for continuously directing the discharge of the pump into the surge tank. For this reason, in order that the platen may be brought to rest at the end of its return stroke when desired, means must be provided for diverting the discharge of the high pressure pump away from the reversing valve.

To this end I provide the discharge line 4 of the high pressure circuit with a bypass valve I, which includes a valve casing 140, a valve chamber 141 within the casing, and a piston valve 142 slidably mounted in the chamber and having spaced heads 143 and 144 located at opposite ends of the piston valve. As shown in Figure 3, the valve chamber is open at its left hand end, is closed at its right hand end, and adjacent the latter end of the casing is provided with a port 145 communicating with the surge tank. Intermediate the port 145 and the open end of the valve chamber the latter communicates with the pipe line 4. It will be observed that when the piston valve is in the position shown in Figure 3, the discharge of the pump 1 will be blocked by the heads 143 and 144 of the valve, so that fluid will be directed to the reversing valve 5. When the piston valve is moved to the right as viewed in Figure 3, the head 144 will pass beyond the port 145 and will place the pipe line 4 in communication with the surge tank 2 by means of the valve chamber 141 and the port 145. The fluid discharged from the pump 1 will then be diverted from the reversing valve and will be returned to the surge tank.

Pressure responsive means, to be later described, are provided for opening the bypass valve I to divert the pump discharge from the reversing valve when the platen reaches the end of its return stroke. At

this time the push-back cylinders will be filled with fluid, and, in order that the weight of the platen will not cause the latter to coast downwardly and expel the fluid 5 from the push-back cylinders and the reversing valve, the pipe line 4 is provided with a check valve 145^a arranged to permit flow of fluid from the pump to the reversing valve, but to prevent flow of fluid from the 10 reversing valve to the by-pass valve I.

The pressure responsive means for actuating the by-pass valve includes a pressure chamber 146 formed in one end of the valve casing 140, a piston 147 slidably mounted in 15 the chamber, and a stem 148 connecting the piston to the piston valve 142. Hydraulic connections including a pipe line 148^a, a platen actuated valve 149, and pipe lines 150 and 151 communicating with opposite 20 ends of the pressure chamber 146, are connected between the low pressure pilot circuit and the chamber for actuating the piston 147.

The platen actuated valve includes a casting 152, a valve chamber 153 therein, a piston valve 154 mounted for sliding movements in the chamber, a spring 155 interposed between one end of the piston valve and one end of the chamber for urging the 30 valve toward the left, and a stem 156 extending through an opening in the other end of the casing and adapted to be actuated by platen operated means for moving the valve toward the right against the pressure of the 35 spring. The right hand end of the valve chamber is vented by means of an opening 157 extending through the piston valve, and a pipe 158, which affords constant communication between the surge tank and the 40 left hand end of the valve chamber.

When the piston valve 154 is in the position shown in Figure 3, pressure fluid from the low pressure pilot circuit will be directed into the right hand end of the pressure 45 chamber 146 by means of the pipe 148^a, the valve chamber 153, and the pipe 151, thereby maintaining the piston valve 142 of the by-pass valve in the position shown in Figure 3. When the piston valve 154 50 of the platen actuated valve is moved to the right, pressure fluid from the low pressure circuit will enter the left hand end of the pressure chamber 146 by means of the pipe 148^a, the valve chamber 153, and the pipe 150, thereby moving the piston valve 142 55 of the by-pass valve toward the right, thus diverting the discharge of the high pressure pump from the reversing valve and returning the fluid to the surge tank.

60 For moving the piston valve 154 to the right against the pressure of the spring 155, I provide mechanical platen-actuated means adapted to engage the end of the stem 156. As shown in Figure 1, these means include 65 a vertically disposed operating rod 159 slid-

ably mounted in lugs 160 and 161 on the stationary table C and the press head D, respectively, the downward movement of the rod being limited by a collar 162 adjustably fixed to the rod and adapted to abut the 70 lug 160. The rod is constantly urged to its lowermost position by gravity, and also by means of a coiled spring 163 mounted on the rod between the lug 161 and a collar 164 also on the rod. A boss 165 fixed to the 75 platen F is arranged to slide freely on the rod 159 and is adapted to engage a collar 166 on the rod when the platen has reached a predetermined point in its upward travel, thereby lifting the rod. A bell crank lever 80 167 pivotally connected to the press head D as at 168 has one of its arms pivotally connected to the rod 159. The other arm thereof is provided with a rounded head 169 adapted to engage the stem 156 of the platen 85 actuated valve and to move it inwardly against the pressure of the spring 155 when the rod 159 is lifted.

The upper end of the rod 159 is provided with spring cushioning means identical to 90 those with which the rod 113 is provided. Since said means have been described in detail in connection with the description of the rod 113, it will not be necessary to describe them again in connection with the rod 159. 95

Operation

If it is desired that the press operate under full automatic control, the collar 119 is adjusted to such a position on the operating rod 113 that the collar will be engaged by the boss 118 on the platen as the platen approaches the end of its upward or return stroke, and the motor driving the pump will then be started. 100

Assuming that this adjustment of the collar 119 has been made, that the motor driving the pump has been started, and that the reciprocating platen is traveling downward, the piston valve 44 of the reversing valve 5 will be in the position shown in Figure 5 and the piston valve 23 of the surge shifting valve 8 will be in the position shown in Figure 2, and the operation of the various parts comprising the automatic control 110 mechanism will be as follows: 115

The pump 1 is set to discharge fluid under pressure through the pipe line 4 into the reversing valve 5, the fluid passing from the pipe line 4 through the port 53, the valve chamber 43, the port 50, and the pipe line 6, and into the booster cylinders 7, the fluid pressure thereby exerted in said booster cylinders causing the platen to move downwardly. During this part of the down 120 stroke of the platen, fluid from the surge tank 2 will flow through the port 20, the valve chamber 19, and the port 22 into the main cylinder 21. While the down stroke 125 of the platen is being performed the fluid 129

which entered the push back cylinder 10 during the preceding up stroke must escape from said cylinders into the surge tank. This is accomplished by means of the pipe line 9, the port 51, and the openings 55 and 56 in the piston valve 44.

When the platen encounters resistance to its downward movement, the fluid pressure in the pipe lines 4 and 6 will build up until 10 it reaches a predetermined value, at which time said pressure, acting on the tail rod 24 of the surge shifting valve 8, will cause the piston valve 23 to move to the left from the position shown in Figure 2, thereby expelling 15 the fluid contained in the chamber 28 through the ports 35 and 34 of the check valve 32. It is to be noted that, by adjusting the plug 38 to vary the pressure exerted on the ball 36 by the spring 37, the fluid 20 pressure in the pipe line 6 necessary to move the piston valve to the left may be varied at will.

After the piston valve 23 has been moved to the left as described above, the valve 25 chamber 19 will be shut off from communication with the port 20 by the right hand end portion of said valve, and at the same time said valve chamber 19 will be placed in communication with the pipe line 6 by 30 means of the passage 26 and the bore 25, which bore has been vacated by the tail rod 24. The main cylinder 21 now receives fluid under pressure from the valve chamber 19 through the port 22. As has been heretofore 35 stated, the chamber 93 of the pilot valve 14 is in constant communication with the pipe line 6 by means of the pipe 112, so that, when the platen encounters further resistance to its downward travel resulting in a 40 further building up of pressure in the high pressure circuit, the pressure will increase correspondingly in said chamber until a predetermined pressure has been reached, at which time the plunger 96 will be moved to 45 the right by the pressure in said chamber and against the force of the spring 108.

It is to be understood that, while the platen has been descending to perform its pressing stroke, the piston valve 70 has been 50 in a position to the left of that shown in Figure 4, so that the pipe line 13 of the low pressure circuit has been in communication with the pipe line 16. Since the piston valve 44 has been stationary during this pressing 55 stroke of the platen, fluid from the low pressure circuit has not been flowing through the pipe line 16, but the discharge of the pump 12 has been by-passed by means of the relief valve and returned to the surge tank in 60 the manner described above. When the plunger 96 of the pilot valve 14 is moved to the right as viewed in Figure 4, the stem 97 will contact the piston valve 70 and move 65 said valve to the position shown in Figure 4. Fluid from the low pressure circuit will

now pass through the pipe 13 and the pipe 17 into the right hand end of the pressure chamber 60 of the reversing valve 5 and will force the piston 64 to the left as viewed in Figure 5, thus shifting the piston valve 44 70 to place the port 53 in communication with the pipe line 9. In this new position of the piston valve 44, the pipe line 4 will communicate with the push back cylinders 10 by means of the port 53, the valve chamber 43, 75 the port 51, and the pipe line 9, and the pipe line 6 will communicate with the chamber 57 so that the booster cylinders will communicate with the surge tank by means of the pipe line 6, the port 50, the chamber 57, 80 and the openings 58.

Fluid under pressure in the pipe line 9 and in the chamber 31 of the surge shifting valve will now act on the tail rod 27 causing the piston valve 23 to be moved to the right, 85 or, in other words, to the position shown in Figure 2. While the piston valve is moving to the right, fluid from the surge tank 2 will enter the chamber 28 through the check valve 39, as hereinbefore described. The fluid under pressure entering the push back cylinders 10 from the pipe line 9 causes the platen to move upwardly, and the fluid in the main cylinder 21 will be expelled therefrom into the surge tank through the port 22, the valve chamber 19, and the port 20. During the upward movement of the platen, fluid will be expelled from the booster cylinders through the pipe line 6, the port 50, the valve chamber 43, the chamber 57, the 100 openings 58, and into the surge tank 2.

When the platen approaches the limit of its return stroke, the boss 118 carried by the platen will strike the collar 119 on the operating rod 113, lifting the operating rod and causing the bell crank lever 125 to be swung in a clockwise direction as viewed in Figures 1 and 8, thereby forcing the stem 71 of the pilot valve inwardly and shifting the piston valve 70 thereof to the left as viewed in 110 Figure 4.

In this position of the piston valve 70, fluid will pass from the low pressure circuit through the pipe line 13, the valve chamber 66 of the pilot valve, and the pipe line 16 115 into the pressure chamber 60 of the reversing valve, thereby moving the piston 64 to the right as viewed in Figure 5, and shifting the piston valve 44 to the position shown in Figure 5. With the valve 44 in this position, the platen will begin another pressing stroke which will be performed in the same manner as the one already described, and obviously the press will continue to operate in this manner as long as the motor driving the 120 pump is running.

When it is desired that the press operate semi-automatically, that is, in such a way that the platen will perform one pressing operation and then return to its uppermost 130

position and stop, the collar 119 on the operating rod 113 is loosened and moved to a position in which it will not be engaged by the boss 118, and the collar 166 is moved 5 down on the rod 159 to a position in which it will be engaged by the boss 165 when the platen approaches the end of its return stroke. Assuming that the platen is on its downward or pressing stroke, the completion 10 of the downward stroke and the start of the return stroke will be executed in the same manner as that described in connection with the full automatic operation of the press. When the platen has reached a predetermined point on its return stroke, the boss 15 165 will engage the collar 166 and raise the rod 159, thereby rocking the bell crank lever 167 in a counter-clockwise direction as viewed in Figure 1, thus moving the stem 20 156 to the left as viewed in Figure 1 and to the right as viewed in Figure 3. Pressure fluid from the low pressure pilot circuit will then be admitted to the left hand end of the pressure chamber 146 and will move the 25 piston valve 142 of the by-pass valve to the right, thereby diverting the discharge of the pump from the reversing valve and returning it to the surge tank. With the valve 142 in its right hand position, fluid discharged by the pump will be freely bypassed to the surge tank through the medium of the pipe 4, the valve chamber 141, and the port 145. It will be noted that the 30 piston valve 142 is movable to a definitely closed position as shown in Figure 3 and to a definitely and fully open position when moved to the right from the position shown in Figure 3. This movement from the closed to the fully open position will be 35 interrupted, so that, when once the platen has reached a point sufficient to cause opening of the platen-controlled valve 154, the by-pass valve 142 will be completely opened to by-pass fluid to the surge tank at substantially no pressure. As a result of this uninterrupted opening movement of the valve, 40 there will be no time in which the pump discharges against a throttled or restricted by-pass. As has already been described, the 45 check valve 145^a will, at this time, maintain the fluid in the push-back cylinders so that the platen will be held at rest. If, however, there should be some leakage in the system, so that some of the fluid in the 50 push-back cylinders escapes therefrom, the platen will begin to descend. As soon as the platen has descended to an extent to permit the operating rod 159 to be lowered and to thereby rock the bell crank lever 167 in a clockwise direction as viewed in Figure 1, the piston valve 154 will be moved to the left as viewed in Figure 3 by means of the spring 155, and the low pressure fluid will then act to close the by-pass valve so that 55 fluid from the high pressure pump will be 60 65

directed to the reversing valve and the push-back cylinders until the platen has been returned to its uppermost position, at which time the by-pass valve will again be opened. It is therefore apparent that the by-pass 70 valve I, the valve 149 and the check valve 145^a are so arranged as to maintain the platen at or near the upper end of its stroke until the reversing valve is shifted to cause the platen to perform another pressing stroke, even if there are some leaks in the system. 75

To cause the platen to perform another pressing stroke, the lever 132 is swung toward the right, thereby raising the rod 113 and moving the stem 71 of the pilot valve inwardly. This results in the shifting of the piston valve 44 to the position shown in Figure 5, thus placing the pipe line 4 in communication with the pipe line 6 and with the 80 booster cylinders. The platen will then start downwardly on its pressing stroke and will be returned to its upper position and again brought to rest in the manner already described. 85

Although I have illustrated a press provided with a platen especially adapted for performing compressing operations it is to be understood that the invention described herein may be embodied in presses 90 used for punching, forging, shearing, or other like purposes and that the term "platen" is intended to cover any tool, die, or other appliance with which a press embodying my invention might be provided. 95 Other modifications in construction and arrangement of parts may be also made without departing from the scope of my invention. 100

I claim:

1. The combination with a hydraulic press including a reciprocating platen; of a continuous discharge pump; means forming with the press and the pump a hydraulic circuit; a reversing valve operatively connected in said circuit for controlling the direction of movement of the platen; means for moving the reversing valve when the platen reaches the end of its pressing stroke to effect a return of the platen; a by-pass valve operatively connected in said circuit and adapted to open when the platen reaches the end of its return stroke for diverting the pressure fluid from the press to thereby bring the platen to rest at the end of the return stroke thereof simultaneously with the continued discharge of the pump; and hydraulic means controlled by the platen for operating said by-pass valve from its closed to its fully open position and vice versa. 110

2. The combination with a hydraulic press including a reciprocating platen; of a continuous discharge pump; means forming with the press and the pump a hydraulic circuit; a reversing valve operatively con- 115 120 125 130

nected in said circuit for controlling the direction of movement of the platen; means for moving the reversing valve when the platen reaches the end of its pressing stroke to effect a return of the platen; and a by-pass valve operatively connected in said circuit and adapted when open to divert the pressure fluid from the press to thereby bring the platen to rest; fluid pressure responsive means connected to said by-pass valve and adapted to move the latter from its closed to its fully open position; and means for supplying fluid under pressure to said pressure responsive means when the platen reaches a predetermined point on its return stroke to move the by-pass valve to its fully open position.

3. The combination with a hydraulic press including a reciprocating platen; of a continuous discharge pump; means forming with the press and the pump a hydraulic circuit; a reversing valve operatively connected in said circuit for controlling the direction of movement of the platen; means for moving the reversing valve when the platen reaches the end of its pressing stroke to effect a return of the platen; and a by-pass valve operatively connected in said circuit and adapted when open to divert the pressure fluid from the press to thereby bring the platen to rest; a pressure chamber; a reciprocable piston mounted therein and connected to the by-pass valve and adapted to open and close the latter; means adapted to be connected to a source of fluid pressure and adapted to be connected to said chamber on either side of the piston; and means controlled by the platen for directing pressure fluid to the chamber on one side of the piston to move the by-pass valve to its fully open position, and for directing fluid to the chamber on the opposite side of the piston to close said valve.

4. The combination with a hydraulic press including a reciprocating platen; of a continuous discharge pump; means forming with the press and the pump a hydraulic circuit; a reversing valve operatively connected in said circuit for controlling the direction of movement of the platen; means for moving the reversing valve when the platen reaches the end of its pressing stroke to effect a return of the platen; and a by-pass valve operatively connected in said circuit and adapted when open to divert the pressure fluid from the press to thereby bring the platen to rest; a pressure chamber; a reciprocable piston mounted therein and connected to the by-pass valve and adapted to open and close the latter; a source of fluid pressure; hydraulic connections between said source and the chamber and including a platen operated valve interposed between the by-pass valve and said source of pressure, said platen operated valve being

normally in a position to direct pressure fluid to said chamber on one side of the piston to maintain the by-pass valve closed; and means adapted to cooperate with the platen and the platen operated valve to move the latter to a position wherein pressure fluid will be directed to said chamber on the other side of the piston to move the by-pass valve to its fully open position.

5. The combination with a hydraulic press including a reciprocating platen; of a continuous discharge pump; means forming with the press and the pump a hydraulic press-operating circuit; a reversing valve operatively connected in said circuit; a source of fluid pressure; a pilot valve operatively connected to said source of fluid pressure; pressure responsive valve-actuating means associated with said reversing valve; means adapted to provide fluid communication between the pilot valve and said valve actuating means for admitting fluid from said source of pressure to said valve-actuating means to shift the reversing valve when the pilot valve is shifted; means for shifting the pilot valve when the platen approaches the end of its pressing stroke; a by-pass valve in said press operating circuit adapted when open to divert fluid from the press during continued discharge of the pump; fluid pressure responsive means associated with said by-pass valve and adapted to have communication with said source of pressure; and platen operated means for establishing communication between said source of pressure and said fluid pressure responsive means when the platen approaches the end of its return stroke for opening the by-pass valve.

6. The combination with a hydraulic press including a reciprocating platen; of a continuous discharge pump; means forming with the press and the pump a hydraulic press-operating circuit; a reversing valve operatively connected in said circuit; a source of fluid pressure; a pilot valve operatively connected to said source of fluid pressure; pressure responsive valve-actuating means associated with said reversing valve; means adapted to provide fluid communication between the pilot valve and said valve actuating means for admitting fluid from said source of pressure to said valve-actuating means to shift the reversing valve when the pilot valve is shifted; means for shifting the pilot valve when the platen approaches the end of its pressing stroke; a by-pass valve in said press operating circuit adapted when open to divert fluid from the reversing valve during continued discharge of the pump; pressure responsive means associated with said by-pass valve and adapted to move the latter to open and closed positions; means adapted to afford communication between said source of pressure and

said pressure responsive means; a platen operated valve interposed in said last named means, and movable to either of two positions to direct pressure fluid from said 5 source of pressure to said pressure responsive means to move the by-pass valve to open and to closed positions; means for normally maintaining said platen operated valve in one position; and platen actuated 10 means for moving said valve to its other position.

7. The combination with a hydraulic press including a reciprocatory platen; of a continuous discharge pump; a surge tank; 15 means forming with the press, the surge tank, and the pump a high pressure press-operating hydraulic circuit; a reversing valve operatively connected in said circuit and positioned within the surge tank; a low 20 pressure hydraulic pilot circuit; a pilot valve operatively connected in said low pressure circuit and positioned outside of the surge tank; pressure responsive valve-actuating means associated with said reversing valve; hydraulic connections between the pilot valve and said valve actuating means for admitting fluid from said low pressure circuit to said valve-actuating means to shift the reversing valve when the 25 pilot valve is shifted; means for shifting the pilot valve when the platen approaches the end of its pressing stroke; a by-pass valve in said high pressure circuit adapted when open to divert the high pressure fluid 30 from the reversing valve during continued discharge of the pump, said valve being positioned within the surge tank; pressure responsive means associated with said by-pass valve and adapted to move the latter to open and 35 closed positions; hydraulic connections between the pilot circuit and said pressure responsive means; a platen operated valve interposed in said hydraulic connections, and movable to either of two positions to 40 direct pressure fluid from the low pressure circuit to said pressure responsive means to move the by-pass valve to open and to closed positions, said platen operated valve being positioned outside of the surge 45 tank; means for normally maintaining said platen operated valve in one position; and platen actuated means for moving said valve to its other position.

8. The combination with a hydraulic press 55 including a reciprocatory platen; of a continuous discharge pump; means forming with the press and the pump a hydraulic circuit; a reversing valve operatively connected in said circuit for controlling the direction of 60 movement of the platen; means for moving the reversing valve when the platen reaches the end of its pressing stroke to effect a return of the platen; a by-pass valve operatively connected in said circuit and adapted 65 to be opened when the platen reaches the

end of its return stroke for diverting the pressure fluid from the press to thereby bring the platen to rest at the end of the return stroke thereof simultaneously with the continued discharge of the pump; hydraulic means controlled by the platen for operating said by-pass valve from its closed position to its fully open position and vice versa; and means for maintaining the platen at rest. 70 75

9. The combination with a hydraulic press including a reciprocatory platen; of a continuous discharge pump; means forming with the press and the pump a high pressure press-operating hydraulic circuit; a reversing valve operatively connected in said circuit; a low pressure hydraulic pilot circuit; a pilot valve operatively connected in said low pressure circuit; pressure responsive valve-actuating means associated with said reversing valve; hydraulic connections between the pilot valve and said valve actuating means to shift the reversing valve when the pilot valve is shifted; means for shifting the pilot valve when the platen approaches the end of its pressing stroke; a by-pass valve in said high pressure circuit adapted when open to divert the high pressure fluid from the reversing valve during continued discharge of the pump; pressure responsive means associated with said by-pass valve and adapted to move the latter to open and closed positions; hydraulic connections between the pilot circuit and said pressure responsive means; a platen operated valve interposed in said hydraulic connections, and movable to either of two positions to direct pressure fluid from the low pressure circuit to said pressure responsive means to move the by-pass valve to open and to closed positions; means for normally maintaining said platen operated valve in one position; platen actuated means for moving said valve to its other position; and means connected in said high pressure circuit for maintaining the platen at rest when the by-pass valve is open. 90 95 100 105 110

10. The combination with a hydraulic press including a reciprocatory platen; of a continuous discharge pump; means forming with the press and the pump a hydraulic press-operating circuit; a reversing valve operatively connected in said circuit; a source of fluid pressure; a pilot valve operatively connected to said source of fluid pressure; pressure responsive valve-actuating means associated with said reversing valve; means adapted to provide fluid communication between the pilot valve and said valve actuating means for admitting fluid from said source of fluid pressure to said valve-actuating means to shift the reversing valve when the pilot valve is shifted; means 115 120 125 130

- for shifting the pilot valve when the platen approaches the end of its pressing stroke; means for diverting pressure fluid from the reversing valve when the platen reaches a predetermined point on its return stroke to thereby bring the platen to rest simultaneously with the continued discharge of the pump; fluid pressure actuated means for operating said last named means and a check valve interposed in said press operating circuit between the pump and the reversing valve for maintaining the platen at rest when the pressure fluid diverting means is open.
15. 11. The combination with a hydraulic motor including a reciprocable ram, and a co-operating cylinder; of a pump; means forming a hydraulic circuit with said motor and pump; a reversing valve in said circuit for controlling the direction of movement of said ram; a normally closed by-pass valve connected in said circuit and adapted when open to effect free by-passing of fluid at substantially no pressure; and fluid pressure actuated means controlled by movement of said ram for moving said by-pass valve to its fully open position when the ram approaches the end of a stroke.
12. The combination with a hydraulic motor including a reciprocable ram and co-operating power cylinder; of a pump; means forming a hydraulic circuit with said pump and motor for operating said ram; a normally closed fluid pressure responsive by-pass valve in said circuit; and a ram-operated valve for controlling movement of said by-pass valve.
13. The combination with a hydraulic motor including a reciprocable ram and co-operating power cylinder; of a pump; means forming a hydraulic circuit with said pump and motor for operating said ram; a by-pass valve interposed between said circuit and an exhaust, said valve including a casting formed with a bore and a balanced piston valve mounted to slide therein; a pressure responsive double acting piston connected to said piston valve, means for supplying fluid under pressure to said piston for operating the piston valve in both directions; and a ram operated valve for controlling application of pressure to said piston.
14. The combination with a hydraulic press including a reciprocatory platen and hydraulic platen actuating means for reciprocating the platen; of a surge tank, a pump; means forming with the platen actuating means, surge tank, and pump a hydraulic circuit; control valve means in said circuit for controlling communication between said tank and said platen actuating means, and also between said pump and said platen actuating means to effect a complete reciprocation of said platen; a platen controlled by-pass valve operatively connected in said circuit and adapted to place said pump in communication with said tank independently of said control valve means; and means for operating said by-pass valve when the platen approaches the end of a return stroke and irrespective of the pressure in said circuit.
15. The combination with a hydraulic press including a reciprocatory platen and hydraulic platen actuating means for reciprocating the platen; of a surge tank; a pump; means forming with the platen actuating means, surge tank, and pump a hydraulic circuit; control valve means in said circuit for controlling communication between said tank and said platen actuating means, and also between said pump and said platen actuating means to effect a complete reciprocation of said platen; a pressure responsive by-pass valve operatively connected in said circuit and adapted to place said pump in communication with said tank independently of said control valve means; and means for automatically applying fluid pressure to said by-pass valve for moving the latter when the platen approaches the end of a return stroke irrespective of the pressure in said circuit.
- In testimony whereof, I have hereunto subscribed by name.
- WALTER ERNST.
